STRUCTURAL TOY ELEMENT

Bernard Frishberg, Flushing, N. Y.

Application December 4, 1953, Serial No. 27,921

Term of patent 14 years

(Cl. D34—15)

FIG. 1.

FIG. 2.

FIG. 3.

To all whom it may concern:

Be it known that I, Bernard Frishberg, a citizen of the United States, residing at Flushing, Queens County, and State of New York, have invented a new, original, and ornamental Design for a Structural Toy Element, of which the following is a specification, reference being had to the accompanying drawings, forming part thereof, in which:

Figure 1 is a perspective view of a structural toy element showing my new design;

Fig. 2 is a bottom plan view thereof; and,

Fig. 3 is an end elevation of the element.

I claim:

The ornamental design for a structural toy element, substantially as shown.
